UNITED STATES PATENT OFFICE

JOHN C. HAAG, OF LANSING, MICHIGAN.

MACHINE FOR MAKING PICKET FENCES.

SPECIFICATION forming part of Letters Patent No. 380,482, dated April 3, 1888.

Application filed December 2, 1887. Serial No. 256,770. (No model.) Patented in Canada September 1, 1887, No. 27,539.

To all whom it may concern:

Be it known that I, JOHN C. HAAG, a citizen of the United States, residing at Lansing, in the county of Ingham and State of Michigan, have invented certain new and useful Improvements in Machines for Making Picket Fences, of which the following is a specification, reference being had therein to the accompanying drawings.

10 This invention relates to certain new and useful improvements in machines for making picket fences, for which I have obtained Letters Patent in Canada September 1, 1887, No. 27,539.

15 The object of the invention is to provide a machine by means of which pickets may be secured to a wire strand or strands by means of a binding-wire which incloses three sides of the picket and is wrapped with its ends 20 around the wire strand, to which the picket is thereby secured. The machine is likewise adapted to all similar uses, such as, for instance, securing the telegraph or telephone wires to insulators or posts and for various purposes.

25 My invention consists in the arrangement or construction of the different parts, whereby the operator can by the use of my machine fasten the binding-wire at a single operation 30 around the picket, holding the picket at the same time firmly against the strand of the fence, all as more fully hereinafter set forth.

Figure 1 is a perspective view of my improved device as it appears in use. Fig 2 is 35 a side elevation. Fig. 3 is a plan, and Fig. 4 is a cross-section through the apertures that sustain the binding-wire.

40 In the accompanying drawings, which form a part of this specification, A is a bifurcated frame, preferably of cast-iron, substantially of the shape known, and this frame has a downwardly-projecting handle, B, by means of which the device may the more readily be adjusted upon the wire strand of the fence.

45 Within the bifurcated frame are journaled the wrapping-wheels C C' and the drive-wheel D, which intermeshes therewith and communicates motion to them by means of a so-called "crank-brace," G, and to which the bevel- 50 wheel D is fixedly secured at the inner end.

The wrapping-wheels C C' and drive bevel-

wheel D are at right angles to each other, and are what are called "bevel gear-wheels," and they form a suitable opening between them, as shown in Fig. 1, to embrace the picket. Each 55 of the wrapping-wheels is provided with a hub, E, which forms a bearing for the wrapping-wheels in the frame A. Each wrapping-wheel, with its hub, is provided with a radial slot, a, which, when the wheels are in a certain position, register with the slots c in the front ends of the frame A.

Through the wrapping-wheel C, substantially in the direction of its axis and at one side thereof, in an inclined direction, is formed 65 an aperture, b, in which is secured in any convenient manner a steel bushing, d. A similar aperture, b', is formed in the wheel C', and this aperture is preferably diametrically opposite the aperture b, and is closed in the outer end 70 so as to form a socket, and is properly recessed to receive the steel bushing h.

In practice the binding-wire, which is cut of a suitable length, is passed through the aperture b and its end inserted in the aperture 75 b' in the opposite wrapping-wheel. When the device is in the position shown in Fig. 1 and has just been placed upon the wire strand, the aperture in the wheel C is above and the aperture b' below the center of the wheels C C', and 80 it will readily be seen that by not having the aperture b' entirely through the wheel C' the binding-wire cannot accidentally slip through. Upon motion being given to the crank the wrapping-wheels are rotated in opposite di- 85 rection, and the ends of the binding-wire are firmly wrapped around the wire strand and the picket securely fastened to the wire strand.

The overhanging guide I serves as a means for keeping the picket away from the wrap- 90 ping-wheel, so that in the operation of the de- vice the picket will not be marred.

The employment of the steel bushings de- 95 scribed prevents the binding-wires from wearing the apertures through the wrapping-wheels, and if the bushings themselves become too much worn they can readily be removed and replaced with new ones.

What I claim as my invention is—

1. In a machine of the kind described, the combination of two wrapping-wheels having a common axis of rotation and provided with

corresponding radial slots and inclined eccentric apertures, a bifurcated frame to which said wrapping-wheels are journaled and having slots communicating with the radial slots 5 in the wrapping-wheels, suitable mechanism for revolving the wrapping-wheels, and the overhanging guides I, secured to the bifurcated frame, all arranged to operate substantially as described.

10 2. In a machine of the kind described, the combination of two wrapping-wheels having a common axis of rotation and provided with corresponding radial slots and inclined eccentric apertures, one of said apertures being closed at one end, a bifurcated frame to which said wrapping-wheels are journaled, having slots communicating with the radial slots in the wrapping-wheels, the intermeshing drive-wheel placed at right angles to the wrapping-wheels, and the hand-brace for communicating motion thereto, substantially as described.

3. In a machine of the kind described, the combination of two wrapping-wheels, C C', having a common axis of rotation, the wheel C, having an inclined eccentric aperture, b, and a bushing, d, in said aperture, and the wheel C', having inclined aperture b', closed at one end and receiving the bushing h, the bifurcated frame A, having slots communicating with radial slots a in the said wrapping-wheels 25 C C', the drive-wheel D, brace G, and handle B, the parts being constructed, arranged, and operating substantially in the manner and for the purposes described.

In testimony whereof I affix my signature, 30 in presence of two witnesses, this 25th day of October, 1887.

JOHN C. HAAG.
